UNITED STATES PATENT OFFICE.

JOSEPH WEBB, OF BEAVER, PENNSYLVANIA.

DESIGN FOR A GLOBE OR SHADE.

SPECIFICATION forming part of Design No. 20,296, dated November 11, 1890.

Application filed October 2, 1890. Serial No. 366,886. Term of patent 3½ years.

To all whom it may concern:

Be it known that I, JOSEPH WEBB, a subject of the Queen of Great Britain, residing at Beaver, in the county of Beaver and State 5 of Pennsylvania, have invented a certain new and useful Design for Articles of Glassware; and I do hereby declare the following to be a full, clear, and exact description of the invention, reference being had to the accompanying drawing, which forms part of this specification.

This invention has relation to designs for hollow articles of glassware, such as globes, shades, &c.

15 The design constituting my invention is particularly applicable to vessels or articles of substantially hemispherical shape; and it consists of a shade, globe, or other similarly-shaped article bearing on its outer surface a 20 series of elliptic lanceolate figures having convex or rounded surfaces and arranged side by side with their pointed ends above and

below and with their convex surfaces on the outside.

The accompanying illustration is a perspective view of a globe or shade embodying my design.

The body A of the shade is of substantially hemispherical form and bears on its outer surface the elliptic lanceolate projections or 30 figures B B.

Having described my invention, I claim—

The design for a hollow article of glassware, consisting of a substantially hemispherical body bearing on its outer surface a series of 35 convex elliptic lanceolate figures arranged substantially as described and shown.

In testimony that I claim the foregoing I have hereunto set my hand this 20th day of September, 1890.

JOSEPH WEBB.
